ELECTRIC CAM SNAP SWITCH

Arthur C. Gaynor, Stratford, Conn., assignor to
Joseph F. Gaynor, Milford, Conn.

Application April 18, 1945, Serial No. 589,026

11 Claims. (Cl. 200—68)

1

This invention relates to electric switches, and more particularly to switches of the type known as slow-breaking, wherein the contacts are not abruptly separated or snapped apart.

In everyday usage, lever-operated switches for household appliances, drop and extension cords and the like are almost universally made with snap-operating contacts, the thought being that such switches may find application in inductive circuits which, particularly in connection with direct current, are commonly known to produce troublesome arcing. While these snap-acting switches have in the past proved to be generally satisfactory, their mechanisms were limited as to useful life, and current capacity for a given size.

In the past, in a large majority of cases, snap switches were employed in connection with alternating current circuits of the type which presented no problem of excessive arcing, and therefore the abrupt or snap separation of the contacts was unnecessary, and indeed undesirable in that it tended to create a large or elongate arc. However, the "feel" of the snap movement of the levers of such switches, and the sound of the snap were desirable characteristics which found public acceptance, and therefore widespread usage.

According to the present invention a lever-type switch mechanism is provided, suitable for use with wiring devices, appliances and the like, which retains the snap or detent action of the lever, but has a long lived extremely simple and economically producible, slow-acting contact mechanism advantageous for the great majority of alternating current uses wherein substantial arcing does not occur. When the slow-opening contacts of the present switch are separated, the arc produced is very small, not elongate as in the case where abrupt separation of contacts is effected by snap-acting mechanisms.

I have found that under ordinary conditions, when the switch of the present invention is employed in an alternating current circuit, the arc at the contacts becomes extinguished before the separation of the latter reaches approximately .005", due to the voltage passing through zero during some part of that movement.

The arc is extremely small, never being greater than .005", as compared with the elongate or

2

drawn-out arcs which may occur when the contacts are abruptly separated and moved apart by snap-action.

In the specific illustrated embodiment of the invention, the contact structure includes a specially-shaped, resilient, biased metal contact-carrying blade acted on at one side by a compression coil spring and at the other side by a crank or lever comprising the switch operator. The parts are thus few in number, and may be of small dimension yet of large current capacity. Due to the simplicity of the contact and operating mechanisms, and the action of the same, the switch is trouble-free in operation, and has a long useful life.

The shape of the resilient blade or arm, and arrangement of the crank or lever operator is such that the latter when moved has imparted to it a snap action, especially pronounced when closing the contacts, and the re-engagement of the latter with each other is accompanied by a certain amount of impact, which functions to dislodge any dirt particles from between the contacts, and insures a positive electrical juncture.

There is thus achieved a "slow-break" switch of simple and economical construction which has desirable electrical characteristics well adapted for alternating current circuits, and which has a snap-acting lever operator convenient in use.

A novel organization is provided in connection with the operating lever of the switch whereby the latter may be mounted in an extremely simple and economical manner for pivotal movement within the switch casing. The mounting is such that the casing may be molded to the desired finished form without the necessity of additional operations such as drilling and the like. Instead, the molding equipment for the casing may be of the usual construction providing recesses and apertures in the molded part which do not prevent the latter from being readily withdrawn from the mold.

In accomplishing this, the operating lever of the switch is provided with bearing plates at each side, in which the lever is pivoted, and the casing is provided with recesses which receive and nest the bearing plates, positioning and preventing the latter from turning. The assembly of the operating lever to the casing is thus a matter of merely pressing into place the lever and bearing

plates. In addition, the plates are provided with lugs which act as stops for limiting the movement of the operating lever.

Other features and advantages will hereinafter appear.

In the accompanying drawings:

Figure 1 is longitudinal section taken through the center of the switch of this invention, showing the parts in open-circuit position.

Fig. 2 is an underside or inside plan view of the upper half of the switch of Fig. 1.

Fig. 3 is a plan view of the lower half of the switch of Fig. 1.

Fig. 4 is a longitudinal section similar to Fig. 1 but showing the parts in closed-circuit position.

Fig. 5 is an exploded perspective view of the operating lever assembly, bottom side up, and

Fig. 6 is a longitudinal section similar to Fig. 1, but showing the contacts about to separate.

Referring to Fig. 1, the switch of the present invention comprises a two-part casing 10 having separable recessed halves or shells 11 and 12 which may be formed of the usual molded insulating material. The casing 10, in addition to housing the switch elements, functions as a base on which the various elements are mounted for cooperation with each other. The switch shown is of the type used in connection with electric cords or lines, or used at the end of a pendant drop cord, and therefore the casing 10 at its ends is provided with channels 13 and 14 through which the electric wires may pass.

The casing halves 11 and 12 may be secured together in any suitable manner, that shown comprising screws 15 extending through apertures in the casing half 12 and threading into metal inserts 16 which are molded into the upper casing half 11.

In the specific embodiment of the invention illustrated herein the upper casing half 11 of the switch is adapted to carry an operating lever 17, together with associated bearing and force-transmitting instrumentalities, and the lower casing half 12 adapted to carry the switching mechanism which is responsive to the movements of the lever 17.

According to the invention, a novel simplified switching and operating mechanism is provided in the casing 10 whereby a comparatively slow "break" or separation of the switch contacts is effected by operation of the manually engageable lever 17, the "make" or re-engagement of the contacts being much faster than the "break," and having a speed wherein there is a degree of impact for causing positive re-establishment of the connection. The mechanism is such that, with the stated contact action, a definite desirable detent and snap action of the lever is produced enabling a user to determine by touch and hearing as well as by sight the functioning of the switch.

Considering again Fig. 1, the switching mechanism carried by the casing half 12 comprises a stationary contact in the form of a resilient metal strip or arm 18 having at one end a contact disk 19, the other end of the arm being secured to a metal insert 20 molded in the casing half 12. The insert 20 is of tubular structure, and is internally threaded to carry a binding screw 21 by means of which electrical connection is made to the arm 18.

For cooperation with the stationary contact disk 19 a movable contact disk 22 is provided, secured to the end of an elongate resilient metal strip or arm 23, the other end of which is fastened to a metal insert 24 molded in the casing half 12. Like the insert 20, the insert 24 is tubular and

internally threaded to receive a binding screw 25 by means of which electrical connection is effected between a wire conductor and the arm 23.

The resilient arm 23 is biased so that it tends to continually yieldably hold the contact disk 22 carried thereby against the stationary contact disk 19. In addition, according to the present invention, a spiral coil spring 26 of the compression type is provided for engagement with the underside of the arm 23 and with the casing half 12 to augment the pressure of the contact disks 19 and 22, the total pressure being sufficient to cause a slight yielding of the stationary arm 18 when the parts are in the position of Fig. 4. As shown in Figs. 1 and 3, the casing half 12 is recessed to provide space and clearance for the switching mechanism comprising the arms 18 and 23, and the coil spring 26.

For the purpose of operating the switching mechanism of the casing half 12 whereby a slow separation of the contact disks 19 and 22 is effected, the resilient switch arm 23 is formed intermediate its ends with a plurality of reverse bends so that the arm has the shape of a flattened M. The center or depressed portion 27 of the M is engaged by the coil spring 26, as shown in Figs. 1 and 4, and the right-hand portion functions as a projection or protuberance, providing a sloping camming surface 28 and a tip portion 29.

Cooperating with the sloping portion 28 and tip 29 of the arm 23 and carried by the lever 17 is a force-transmitting means comprising a pair of rollers 30 mounted on a shaft or pin 31 which latter is carried by a T-shaped plate 32 nesting in a recess 33 of the lever 17. As shown in Figs. 2 and 5, the rollers 30 are disposed on each side of the supporting plate 32, and the latter has an aperture 34 aligning with apertures 35 in the central portion of the lever 17 so that a pin 36 may be extended through all apertures to secure the plate and lever together.

For the purpose of conveniently and economically mounting the lever 17 and associated force-transmitting instrumentalities in the upper casing half 11, a pair of T-shaped bearing plates 37 is provided, having apertures 38 through which the pin 36 may also extend. The lever 17 is therefore pivotally connected to the bearing plates 37.

Referring to Figs. 1 and 2, the upper casing half 11 is provided with an elongate central aperture 39 to accommodate the operating lever 17, and in the opposite walls of the aperture 39 recesses 40 are provided, adapted to receive and nest the bearing plates 37. The recesses 40 do not extend to the outer wall 41 of the casing, but terminate in walls 42, as shown by the dotted lines in Figs. 1 and 4. By this construction the lever 17, bearing plates 37 and roller supporting plate 32 may be secured together by the pin 36, and the entire assemblage pressed into place in the casing half 11, where they will be held by the frictional engagement between the plates 37 and the casing.

When the lever assembly is thus pivotally supported in the casing half 11, the rollers 30 will be in position to engage and operate the resilient switch arm 23, as shown in Figs. 1 and 4, this engagement also preventing the lever and mounting assembly from sliding out of the recesses in the casing half.

Preferably the bearing plates 37 have portions 37a which extend alongside the rollers 30 and past the ends of the pin 31 on which the rollers are carried. The extensions 37a therefore limit

endwise movement of the pin 31, and insure the latter properly carrying the rollers 30 at all times. For the purpose of limiting the arc of movement of the lever 17 the bearing plates 37 are provided with lugs 43 extended inward laterally for engagement with the undersurface 44 of the lever. Referring to Fig. 1 the lever 17 is shown engaging at its undersurface a lug 43 which latter therefore determines the extreme counterclockwise limit of movement of the lever. In Fig. 4 the clockwise limit of movement of the lever 17 is shown, this limit being determined by the other lug 43, of the opposite bearing plate 37.

The operation of the switch is as follows: Referring to Fig. 4, the switch is shown in closed-circuit position, the contact disks 19 and 22 engaging each other under pressure from the spring 26 and also from the bias given the resilient arm 23. The rollers 30 carried by the operating lever 17 may or may not rest against the sloping surface 28 of the resilient arm 23; if they do rest against the surface 28 there will be comparatively little pressure exerted, so that a maximum pressure exists between the contact disks. When operating pressure is first applied to the left-hand end of lever 17, the lever will have moved an extent as shown, moving the arm 23 slightly, and the latter will be followed by the contact 19 for a short distance without separation of the contacts. This action is possible due to the resiliency of the arm 18.

When the lever 17 is moved further, to the position shown in Fig. 1, the rollers 30 will cammingly operate and depress the arm 23 by traversing the inclined surface 28, thereby comparatively slowly separating the disks 19 and 22, the final position of the rollers being somewhat over the tip portion 29 of the arm. For this final position the pin 31 carrying the rollers 30 will have passed a line drawn through the pivot pin 36 and through the point of engagement between the rollers 30 and the tip portion 29, so that a detent is thereby provided for the lever. The open-circuiting movement of the lever 17 causes a slow separation of the contact disks 19 and 22, the speed of break being proportional to the speed of movement of the lever, and being comparatively slow due to the camming effect obtained. As shown in Fig. 1, the spring 26 is compressed an extent, and the arm 23 depressed by the movement of the lever 17 and rollers 30. Due to the slow separation of the contacts, the arc occurring between the latter will be of small size, not over .005" long, and will be extinguished before a greater separation of the contacts occurs, due to the voltage passing through zero immediately after the initial break or during a subsequent voltage reversal. The small arc causes less burning of the contacts than would occur with a large arc such as results from a quick separation of contacts.

The detent action obtained when the pin 31 passes the center line common to the pivot 36 and the point of engagement between the rollers 30 and the arm 23 also tends to complete, with a slight click, the movement of the lever 17 to its final, limited position, because of the pressure on the rollers by the arm. Thus a definite "feel" is imparted to a user, indicating that the switch is in full open-circuit position.

When the lever 17 is moved against the detent for the purpose of closing the switch circuit, the pressure of the spring 26 and resilient arm 23 on the rollers will cause a snap action of the lever

to occur. Thus, after initial movement of the lever, it will be quickly returned to the extreme closed-circuit position shown in Fig. 4 with a distinct snap.

As a result of this action the contact disk 22 will strike the disk 19 with a certain amount of impact, dislodging any dirt and breaking down film which might be on the contacts, so as to insure positive electrical connection.

There is thus provided by the invention a switch having a slow opening and fast closing contact mechanism which is suitable and advantageous where non-inductive, alternating current circuits are to be controlled, and having a distinct detent and snap action of the operating lever.

Variations and modifications may be made within the scope of this invention and portions of the improvements may be used without others.

I claim:

1. An electric switch comprising a base; a stationary contact mounted on the base; a movable contact for engagement with the stationary contact; a resilient arm carrying the movable contact, said arm at one end being anchored to the base and being biased to yieldably hold the contacts together; resilient means engaging the base and resilient arm, for pressing against the latter in a direction to also hold the contacts together; an operating lever pivotally mounted on the base, movable between "on" and "off" positions; and linkage means for flexing the arm and opposing said resilient means to separate the said contacts when the lever is moved from "on" to "off" position, including detent means for yieldably holding the lever in "off" position, said linkage means operating, in response to force from the arm and resilient means, to snap the lever to "on" position so that the contacts may re-engage after the lever has first been moved to overcome said detent means.

2. An electric switch comprising a base; a stationary contact mounted on the base; a movable contact for engagement with the stationary contact; a resilient arm carrying the movable contact, said arm at one end being anchored to the base and being biased to yieldably hold the contacts together; a coil spring engaging the base and resilient arm, and pressing against the latter in a direction to also hold the contacts together; an operating lever pivotally mounted on the base, movable between "on" to "off" positions; and linkage means for flexing the arm and compressing the coil spring to separate the said contacts when the lever is moved from "on" to "off" position, including detent means for yieldably holding the lever in "off" position, said linkage means operating, in response to force from the arm and spring, to snap the lever to "on" position so that the contacts may re-engage after the lever has first been moved to overcome said detent means.

3. An electric switch comprising a base; a pair of metal arms anchored each at one end to the base, said arms extending in line with and toward each other, the adjacent ends overlapping for making electrical contact, and one of said arms being resilient and biased for engagement with the other arm and the other arm being limitedly yieldable in the direction of movement of said first arm during movement thereof to engaged position; an operating lever extending alongside the arms, said lever being pivotally mounted at its center on the base, and having a projection extending from the pivot toward the

resilient arm; and a projection on the resilient arm for camming reversible driving engagement with the projection of the lever whereby opposite movements of the latter causes the said arm to flex and respectively engage and disengage the other arm, closing and opening the circuit of the switch, the said projections being so located that the lever may be moved, when open-circuiting the switch, to cause the centers of the projections to pass each other and prevent automatic return of the lever and reclosing of the switch.

4. An electric switch comprising a base; a pair of metal arms, anchored each at one end to the base, said arms extending in line with and toward each other, the adjacent ends overlapping for making electrical contact, and one of said arms being resilient and biased for engagement with the other arm; a coil spring engaging the base and resilient arm for urging the end of the latter in engagement with the other arm; an operating lever extending alongside the arms, said lever being pivotally mounted at its center on the base, and having a projection extending from the pivot toward the resilient arm; and a projection on the resilient arm for camming reversible driving engagement with the projection of the lever whereby opposite movements of the latter causes the said arm and the coil spring to flex so that the arm respectively engages and disengages the other arm, closing and opening the circuit of the switch.

5. An electric switch comprising a base; a pair of metal arms, anchored each at one end to the base, the other ends of the arms overlapping and touching for making electrical contact, one of said arms being formed with an inclined surface, said arm being resilient and biased for engagement with the other arm; a compression coil spring interposed between the base and the resilient arm, bearing against the latter adjacent the inclined surface thereof for yieldably holding the arms in engagement; and an operating lever pivotally mounted on the base, having a portion engaging the inclined surface of the resilient arm opposite the coil spring for camming operation of the latter whereby opposite movements of the lever and arm-engaging portion thereof cause the said arm and spring to flex so that the arm respectively engages and disengages the other arm, the inclined spring surface and engaging portion of the lever being shaped to provide a detent for yieldably holding the lever in open-circuit position.

6. An electric switch comprising a casing having two separable halves; a pair of metal arms, anchored each at one end to one half of the casing, the other ends of the arms overlapping; contact buttons carried by the overlapping ends of the arms, for making electrical contact between the latter, one of said arms being resilient and biased to yieldably hold the buttons in engagement; a sloping projection on the resilient arm; and an operating lever pivotally mounted on the other casing half and projecting through the same, said lever having a portion engaging the projection of the resilient arm for camming operation of the latter whereby opposite movements of the lever and arm-engaging portion thereof cause the said arm to flex and respectively engage and disengage the contacts.

7. An electric switch comprising a casing having two separable halves; a contact fixedly mounted in one half of the casing; a metal arm mounted in the said casing half, the arm being movable and adapted to engage and disengage

the said contact, and being yieldably maintained in engagement with the latter; a sloping projection on the arm; and an operating lever pivotally mounted on the other casing half and projecting through same, said lever having a portion engaging the projection of the arm for camming operation of the latter whereby opposite movements of the lever and arm-engaging portion thereof cause said arm to respectively engage and disengage the contact.

8. In an electric switch, a support having an opening therethrough; an operating lever extending in said opening, having pivots on each side; a pair of apertured bearing plates carrying the said pivots in the apertures thereof, the walls of the opening of the support being recessed to slidably receive and nest the bearing plates and prevent the latter from turning; and lugs on the bearing plates positioned in the path of movement of said lever for engagement by the lever whereby movement of the latter is confined between two limits.

9. In an electric switch, a support having an opening therethrough; an operating member extending into said opening; bearing plates on opposite sides of the operating member, pivotally connected to the latter, the walls of the opening of the support being recessed to slidably receive and nest the bearing plates and prevent the same from turning; means associated with the bearing plates and operating member for preventing movement of the latter beyond either of two limits; a roller carried by the operating member, for transmitting force therefrom, said member having a shaft on which the roller is rotatable, the said bearing plates extending on opposite sides of the roller and past the ends of the shaft for limiting endwise movement of the latter.

10. An electric switch comprising a casing having two separable halves, one of said halves having an opening therethrough; an operating lever extending through the opening of the said one casing half; bearing plates on opposite sides of the operating lever pivotally connected to the latter, the walls of the opening of the said casing half being recessed to slidably receive and nest the bearing plates and prevent the same from turning; means associated with the bearing plates and operating lever for preventing movement of the latter beyond either of two limits; and contact means carried by the other casing half and operable by the lever whereby when the latter is at one or the other of said limits the contact means are engaged or disengaged respectively.

11. An electric switch comprising a casing having two separable halves, one of said halves having an opening therethrough; a contact fixedly mounted in the other half of the casing; a metal arm mounted in the contact-carrying half of the casing, the arm being movable and adapted to engage and disengage the said contact, and being yieldably maintained in engagement with the latter; a sloping projection on the arm; an operating member extending into the opening of the said one casing half for pivotal movement therein, said member having a portion engaging the projection of the arm for camming operation of the latter whereby opposite movements of the lever and arm-engaging portion thereof cause the said arm to respectively engage and disengage the contact; bearing plates on opposite sides of the operating member, pivotally connected to the latter, the walls of the opening of

9

the said one casing half being recessed to slidably receive and nest the bearing plates and prevent the same from turning; and means associated with the bearing plates and operating member for preventing movement of the latter beyond either of two limits at which the arm respectively engages and disengages the contact.
